UNITED STATES PATENT OFFICE

JACOB RANZ, OF ST. LOUIS, MISSOURI

HEAT DISTRIBUTOR AND TOASTER

Application filed April 10, 1929. Serial No. 354,151.

This invention relates to new and useful improvements in heat distributors and toasters.

The primary objects of the invention are to provide a heat distributor and toaster plate comprising two superposed plate members secured together at spaced points and provided with a plurality of projections or raised surfaces so arranged that the surfaces or projections supporting an article to be heated are spaced from the flame and do not come in direct contact with the surfaces or projections which are subjected to the flame. Thus the heat is equalized and more evenly distributed and the plate prevents undue heat being applied to said article at concentrated areas.

Further objects of the invention are to provide two plate members so secured together that they reinforce each other and prevent buckling thereof so that said plates preserve level surfaces at all times.

Other objects of the invention are to provide a pair of plates, each of which is provided with outwardly raised convolutions or surfaces and to secure said plates together at spaced points by spot-welding or riveting so as to prevent buckling or separation of said plates from each other.

Additional objects of the invention are to provide a heat distributor and toaster plate having a pair of imperforate metal plates welded or riveted together at spaced points and having surfaces projecting outwardly in opposite directions from the normal planes of said plates so as to provide a plurality of oppositely disposed projections or surfaces so as to support the plate and support the article to be heated on different horizontal planes relatively to each other and with respect to the normal planes of said plates.

With these and other objects in view, my invention consists in certain novel features of construction and arrangement of parts, hereinafter more fully described and claimed, and illustrated in the accompanying drawings, in which—

Figure 1 is a top plan view of my improved heat distributor and toaster plate.

Figure 2 is a side elevational view thereof.

Figure 3 is an enlarged cross section taken through the central portion of my plate.

Figure 4 is an enlarged vertical cross section taken through the marginal portion of my plate.

It is known in the art that heretofore both single and double plates have been used in the construction of heat distributors. The single plate has not been found satisfactory as, due to the thin metal wall, the heat was not properly distributed and also the plate had tendency to buckle, thereby distorting the plate and rendering it unfit for use.

In the case of double plates, these have been generally secured together along their edges, the central portion and the intermediate portions of the plates being spaced from each other and left free so that under the action of the heat the central portions of the plates would buckle or bulge outwardly. Furthermore, the plates did not have a sufficient surface contact with each other and consequently considerable heat has been wasted due to the insulating air chamber formed by said plates.

In the present invention I provide a pair of plates securely held together and having considerable surface contact with each other, said plates being so arranged that the article to be heated is suitably spaced from the flame and the surfaces supporting said article do not come in direct contact with said flame.

Referring by numerals to the accompanying drawings, 10 indicates a pair of imperforate metal plates, each of which is provided with a series of concentric convolutions or corrugations 11 which are disposed intermediate a flat central portion 12 and a flat marginal flange or edge portion 13. These corrugations or raised surfaces 11 are presented outwardly whereby the bottoms or low portions 11^a of said convolutions are disposed in the normal plane of the plate, that is, in the same horizontal plane with central portion 12 and marginal flange 13. The apices or high portions 11^b of said convolutions are raised or spaced above or a suitable distance outwardly from the normal plane.

The two plates are placed against each other with the raised surfaces 11^b presented

outwardly or in opposite directions so that the central portions 11 and edge portions 13 are in contact with each other. The plates are then secured together in assembled relation, either by spot-welding or riveting, at suitable points. Preferably these points are located centrally of portions 11 as indicated at 14 and at a series of points arranged near the edges 13 and disposed in a circle as indicated at 15. The raised portions 11^b form air chambers 16 while the low portions 11^a form open air channels 17. When an article, such as a utensil, or a slice of bread to be toasted, is being heated it rests on the high portions 11^b and is spaced from the low or inner portions 11^a by air channels 17. As there are no perforations in either plate, only the lower plates come in contact with the frame and the article itself does not come in direct contact either with the gas flame or with the lower plate. Furthermore, the heat is equalized and distributed throughout the entire area of the plates. The upper plate is heated by direct contact with the lower plate at points spaced from the article and also by means of the air trapped in chambers 16.

The welding or riveting holds the two plates together and said plates are reinforced by each other against distortion by heat, and severe heat tests prove that no warping of plates take effect as the expansion and contraction of the plates is resisted by each other.

Preferably, each plate is formed from sheet metal, stamped and formed to proper shape. Thus the corrugations or convolutions formed in the plate stretch the material and protect the strain of expansion and contraction and reinforce the plate so that it cannot be distorted or bent out of shape under normal conditions.

I claim:

1. A heat distributor and toaster comprising in combination a pair of sheet metal plates, each of said plates having concentric convolutions thereby providing one face of each plate with two surfaces disposed at different horizontal planes, the edge and central portions of each plate being in the same horizontal plane with the inner surface of the apices of inwardly presented convolutions, said plates being arranged with said inner surfaces of said convolutions and said edges and said central portions contacting and welded together at a plurality of spaced points.

2. A heat distributor and toaster comprising in combination a pair of imperforate sheet metal plates, each of which is formed with a series of concentric convolutions presented outwardly from the plane of said plate, the central portion and the edge portion of each plate being left straight and arranged in the same horizontal plane with the apices of the inwardly presented convolutions, the inner faces of said edge and central

portions and the inwardly presented apices of each plate being arranged in contact with the respective parts of the other plate, said plates being secured together at a plurality of spaced points adjacent to the edges thereof.

3. In a device of the class described, the combination of a pair of imperforate sheet metal plates, each plate being formed with a series of concentrically disposed outwardly raised convolutions and having a straight central and edge portions, said plates being arranged together with the edges and the central portions of said plates and the bottoms of said convolutions contacting with each other and secured together at spaced points along said lines of contact, the apices of the outwardly presented convolutions of said plates being arranged at different horizontal planes with respect to each other and with respect to the planes of said plates, whereby said heat distributor is supported on the apices of the downwardly presented convolutions and the utensil is supported on the apices of the upwardly presented convolutions.

4. In a device of the class described, the combination of a pair of imperforate pressed sheet metal plates, each of said plates having the central portion and the edge in the same horizontal plane with each other and the intermediate portion provided with concentric convolutions, the inwardly presented apices of which are arranged in the same horizontal plane with said central and edge portions, said plates being arranged with the inner faces in juxtaposed relation so as to bring said edges and central portions and the apices of the inwardly presented convolutions in contact, said plates being secured together at a central point and at a series of points spaced about adjacent to said edges, the outwardly presented apices of said convolutions being disposed at different horizontal planes to form a plurality of circular air chambers, whereby said heat distributor is in supporting contact with the adjacent surfaces at the apices of its outwardly presented convolutions, the central portions and edge portions of said plates being spaced therefrom.

In testimony whereof I hereunto affix my signature this 29th day of March, 1929.

JACOB RANZ.
